UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON SHOE-HEELS.

1,286,470.

Specification of Letters Patent.

Patented Dec. 3, 1918.

Application filed April 12, 1915. Serial No. 20,769.

To all whom it may concern:

Be it known that I, ERASTUS E. WINKLEY, a citizen of the United States, residing at Lynn, in the county of Essex and State of Massachusetts, have invented certain new and useful Improvements in Machines for Operating on Shoe-Heels; and I do hereby declare the following to be a full, clear, and exact description of the invention, such as will enable others skilled in the art to which it appertains to make and use the same.

This invention relates to machines for operating upon heels of boots and shoes, and more particularly to improvements in machines for automatically shaping the peripheral surfaces of heels.

In Letters Patent of the United States No. 1,102,311 granted to the present applicant July 7, 1914, a machine of the kind in question is disclosed, this machine being adapted to constitute one unit of a system of machines for automatically producing heels, and being designed to perform the shaping operation on rough heels or heel-blocks conveyed to it from a source of supply by a link conveyer upon which the heels are loaded, one heel to each link. As disclosed in said patent, the conveyer is intermittently fed through the space of one link, being brought to rest with a rough heel in position for automatic delivery to the shaping devices of the machine.

Where a machine is supplied with heels from a conveyer, in the manner disclosed in said patent, it is necessary that the heels be removed transversely from the conveyer to the operating instrumentalities of the machine, and that as so transferred and presented to said instrumentalities the heels shall occupy a definite predetermined position. Accordingly said patent discloses means for locating each heel accurately in a definite position on the conveyer prior to the engagement of the heels by the means by which they are transferred from the conveyer to the operative instrumentalities. To contribute to the performance of the function of such means the conveyer in said patent disclosed is provided, on each link, with a flange adapted to serve as a gage against which the heel-block, to be operated upon, may be pressed, to determine its position on the conveyer before the block is transferred. Since the position of such gage

must differ, however, according to the variability in the size of the heels upon which the machine may be required to operate, the means by which the conveyer is intermittently fed, and is retained in stationary position after each feeding movement, is made adjustable, so that at the termination of the feeding movement the flanges in question on the links shall occupy positions determined by such adjustment.

One object of the present invention is to avoid the necessity of gaging the position of the heel-blocks by engagement with any flange or other part of the conveyer. In accordance with this object a feature of the invention contemplates the provision of an arrangement for positioning the heel-block wholly by means external to the conveyer, and the position of the block, after it is so determined, being regardless of the precise position in which the link of the conveyer which supports the heel block is brought to rest.

The novel arrangement by which this is accomplished not only permits a simplification in the means for feeding and locking the conveyer, since it eliminates the necessity of adjustment of such means, but it also is of particular utility where the conveyer which brings the heel-blocks to the heel-shaping machine is employed also to convey the shaped heels away from this machine and to some other machine, such as a heel-compressor, for performing a further operation on the heels. In such an organization any change or adjustment in the position in which the conveyer links are brought to rest prior to the delivery of a heel to the heel-shaping machine is objectionable for the reason that it tends to derange the co-operative relation of the conveyer and the heel-compressor or other machine to which the conveyer carries the heel-blocks from the heel-shaper.

To the foregoing ends it is proposed, in accordance with the present invention, to use a gage-member, for determining the position of the heel-block prior to the transferring operation, which is independent of the conveyer, and independently adjustable to adapt it for operation of heel-blocks of different sizes. In the preferred embodiment of the invention two such gage members are employed, adapted to engage oppo-

site surfaces of a heel-block on the conveyer, both of these gage-members being movable into and out of positions in the path of movement of the heel block on the conveyer, 5 and mechanism is provided to move one of these gage-members toward the other so as to press them in opposite directions against the heel-block and thus determine its position on the conveyer in accordance with the 10 final position to which one or the other of the gage-members is so moved.

Other objects of the invention, and the features of construction by which they are attained, will be more particularly described 15 in connection with the following description of the illustrated embodiment of the invention.

The preferred form of the invention is shown in the accompanying drawings, in 20 which,

Figure 1 is a front-elevation of a heel-shaping machine embodying the present invention;

Fig. 2 is a plan of the front-portion of 25 the machine, including those parts peculiar to the present invention;

Fig. 3 is a plan showing, in detail, a portion of the mechanism for actuating the breast-gage, the parts being shown in a different position from that of Fig. 2; and 30

Figs. 4 and 5 are, respectively, a right-hand and a left-hand side-elevation of the mechanism shown in Fig. 2.

The invention is illustrated, for convenience, as embodied in a heel-shaping machine generally similar to that disclosed in the said Patent No. 1,102,311, and accordingly the construction of the illustrated machine will not be described except in so far 40 as it is necessary for an understanding of so much of it as is novel.

As in said patent, a conveyer-chain (Fig. 2) is supported and guided by sprocket-wheels 22 and 23 journaled on the frame of 45 the machine at the front. The conveyer extends indefinitely to the left of the machine, and is also shown, in the present case, as extending indefinitely to the right of the machine, so that heel-blocks may not only be brought to the machine, but also carried 50 away therefrom to some other machine, such as a heel-compressor.

The conveyer-chain comprises a series of 55 links, each of which has a body in the form of a flat horizontal plate 21, provided with upwardly-extending flanges 24, at its front and end edges, by which the heel-blocks or rough heels to be shaped are confined upon the plate. The heels, both rough and 60 shaped, are indicated by the reference-letter X (see Figs. 1 and 2). The rough heels may be loaded upon the conveyer manually, but preferably they are so loaded by automatic mechanism controlled by a machine 65 by which the heel-blocks are formed.

Each chain-link is provided with downwardly extending flanges 28, which are pivotally connected, at the ends of the links, by transverse pivot-rods 25. The part of the conveyer-chain which is in operative relation with the transferring mechanism is supported upon a guide 27, having an elongated raised central portion on which the pivot-rods 25 rest, as shown in Figs. 4 and 5.

The means for feeding the conveyer intermittently, through the space of one link, is, or may be, substantially the same as disclosed in the said patent, but they may be briefly described herein. The pivot-rods 25

are extended, at the front of the conveyer, to afford bearings for rollers 28. These rollers may be engaged and embraced by two lugs 29, extending from a sleeve 30 which is mounted on a rod 31. The sleeve is free to 35 rock on the rod, but is constrained to move longitudinally with the rod by means of two collars 32 and 33 fixed to the rod and engaging the ends of the sleeve. The rod slides longitudinally in lugs 34 and 35,

which are mounted on the base-portion of the guide-member 27. To impart such movements to the rod a collar 37 is fixed to the rod and pivotally connected with two links 39, which are also pivoted, by a pin 40, to the upper end of cam-lever 41. The lever is pivoted on a shaft 42 mounted on the frame of the machine, and at the lower end of the cam-lever is a roller 43 which 45 engages a cam 44 actuated by a cam-shaft

45. This cam-shaft is rotated by connection with any suitable source of power. When the lugs 29 are in engagement with one of the rollers 28 the longitudinal movement of the slide-rod 31 and the sleeve 30, produced 50 by the cam-mechanism just described, results in a corresponding forward movement of the upper portion of the conveyer, this movement being in the direction indicated by arrows in Fig. 1, and being of the amplitude, in each case, of the length of one link.

Prior to the return-movement of the sleeve 30 it is necessary to disengage the lugs 29 from the roller 28, and this is accomplished by rocking the sleeve on the slide-rod 31. The rocking movement is produced by mechanism comprising a gear-segment 46 on the sleeve, and an elongated gear-segment 47 in mesh therewith. The segment 47 100 is pivotally mounted on a rod 48 fixed in brackets 49 on the frame of the machine. It is provided with an arm 50 which is pivotally connected with the upper end of a rod 51. At the lower end of the rod is a cam-roller 52, which engages a cam 53. This cam is mounted on a transverse cam-shaft (not shown) which also is actuated by connection with the source of power. The cam-mechanism is arranged to rock the sleeve 105 110 115 120 125 130

at the end of the conveyer-feeding movement a direction to disengage the lugs 29 from the roller 28, as shown in Fig. 4 and the slide-rod 31 and the sleeve 30 are then 5 moved longitudinally in a reverse direction, so as to bring the lugs 29 into position directly above the roller 28 on the next link of the conveyer, whereupon the lugs are rocked downwardly into engagement with 10 such roller preparatory to the next feed-movement.

As in the machine disclosed in said patent, means is provided for locking the conveyer against accidental movement between 15 successive feed-movements, but as such locking means is, or may be, in every respect similar to the means disclosed in said patent, no description herein is necessary.

The heels are transferred from the conveyer to the heel-carrier of the machine, and then brought back again after they have 20 been shaped by transferring mechanism comprising two jaws 71 and 72 (Figs. 4 and 5) which are adapted to engage the sides of 25 the heels. These jaws are movable toward and from each other by the operation of mechanism disclosed in the said patent, their original position being apart and on opposite sides of the conveyer, so that a heel block 30 may be brought into the space between them by one of the feed-movements of the conveyer. The jaws are then closed upon the heel between them, and are then moved bodily so as to transfer the heel laterally, from 35 the conveyer to one of the heel-holding clamps of the machine. The clamp is shown in the drawings as comprising a pattern-plate 105, (Fig. 2) upon which the heel rests in an inverted position, and a clamping-jaw 40 106 (Fig. 1) which slides upon a post 108 projecting upwardly from the base 107 on which the pattern-plate rests. These parts are, or may be, all similar to the corresponding parts described in the said patent, and 45 therefore they need not be further described herein.

The mechanism for actuating the jaws of the transferring mechanism includes a yoke 96 carried by a horizontally moving slide 97, 50 and appropriate in and out movements in a horizontal direction are given to these parts by means of a link 98 pivoted to the bottom of the yoke 96, as shown in Fig. 4. This link is pivoted also to the upper end of a lever 99, which is pivotally mounted, at 100, between the ends of two hangers 101 constituting a part of the frame of the machine. At its lower end the lever 99 is connected with cam-mechanism which causes the yoke 96 to be moved precisely as described in the 55 said patent.

In the embodiment of the invention illustrated in the drawings, the gaging mechanism, in which the present invention particularly resides, comprises two fingers for

engaging the heel-block. One of these fingers is in the form of a flat plate 59 arranged to move into the path of movement of the heel-block on the conveyer, so as to be engaged by the rear-surface of the heel 70 which is approaching the delivery mechanism. This finger is secured, at its upper forward corner, to a rod 61 loosely mounted in a socket 62 in a bar 63. The bar 63 constitutes a part of a frame, including side-members 64 and 65 which are joined by the bar 63. The upper rear corner of the finger 59 is fixed to a rod 66, which is mounted to slide through the side-piece of the frame. A spring 67 is coiled around the rod 66, and 80 interposed between the side-member 64 and a collar 68 fixed on the rod. This spring normally holds the finger in its left-hand position, but permits the finger to yield when a heel is pressed against it. A collar 85 69, mounted on the rod 66 outside of the side-member 64, limits the movement of the finger under the influence of the spring.

In order that the shaped heel, which is brought back to the conveyer by the transferring-jaws, may be carried by the conveyer past and beyond the gage-finger 59, it is necessary that the finger be moved into and out of the path of the heel on the conveyer at proper times in the operation of the 95 machine. Accordingly the side-members 64 and 65 of the finger-supporting frame are pivotally mounted on the rock-shaft 48 hereinbefore referred to, so that the frame may be swung to raise and lower the gage-finger. 100 In the illustrated embodiment of the invention the frame and the finger are lowered by the action of gravity, and are raised by mechanism actuated by the yoke 96. As shown in Fig. 5, the side-member 65 of the 105 finger-supporting frame extends outwardly from the rock-shaft 48, and at its outer end it is provided with a roller 170, arranged in the path of movement of a cam-block 171 which is secured to the slide 97. This block 110 is provided with a cam-surface 172 which, when the slide 97 is moved inwardly to transfer a heel from the conveyer to the heel-carrier, engages the roller 170, thus swinging the frame and raising the gage-finger 59 115 out of the path of movement of the heels.

The rear end of the block 171 is shaped to permit free movement of the roller 170 when the slide 97 is in its outer position, and therefore the finger and its supporting frame 120 are free to fall, in so far as the operation of the block 171 is concerned, when the slide has moved to transfer a finished heel from the heel-carrier to the conveyer. At this time, however, the descent of the frame and the finger are prevented by other means, so that the shaped heel may be carried away at the next feeding movement of the conveyer. For this purpose a bracket 73 (Fig. 4) is secured to the collar 37 on the slide-rod 130

31, and the finger-supporting frame is provided with a foot 74, carried by a bridge 75 which is fixed, at its ends, to the side-members of the frame. When the slide-rod 31 is 5 in its left-hand position, prior to the commencement of the feed-movement, the bracket 73 is directly beneath the foot 74, so that it sustains the foot, the frame and the finger. When the rod is moved to the right 10 to feed the conveyer, the foot is supported first by the bracket 73, and later by engagement with the gear-segment 46, which has been rocked upwardly to cause the lugs 29 to engage the roller 28. In this manner the 15 finger 59 is held clear of the path of movement of the shaped heel until the heel has passed beyond the finger. Before the completion of the conveyer feed-movement however, the gear-segment 46 passes out from 20 under the foot 74, whereupon the finger 59 and its carrying-frame descend by gravity, and bring the finger into position to engage the advancing heel-block on the next link of the conveyer.

25 To prevent the finger 59 from rebounding when it falls to its operative position, a latch 77 (Fig. 5) is pivoted on the top of the block 171. This latch is pressed by a spring 79, and it has a shoulder 78 which swings beneath the roller 170 when the roller has 30 reached its uppermost position, thus preventing the roller from descending again in consequence of the tendency of the parts to rebound.

35 The other gage-finger, which may be designated as a breast-gage, since it coöperates with the breast-surfaces of the heels, is in the form of a flat plate 110, shown particularly in Figs. 2 and 5, which is forked in 40 its lower portion. The upper end of the plate is adjustably fixed to a plate 113. The plate 113 is slotted, as shown in Fig. 5, and the breast-gage is provided with a dowel 112 and a screw 111, which move in the 45 slot, and by means of the screw the breast gage may be fixed adjustably at the required height.

The plate 113 is fixed, at one corner, to a 50 rod 114 which slides horizontally through perforations in two parallel side-members 115 and 116. These members are connected, at their inner ends, by a bar 117, and this bar is perforated to receive a sliding rod 118 fixed to the plate 113. The rods 114 and 118 55 guide the plate 113 and the breast-gage in horizontal movement toward and from the gage-finger 59.

The side-members 115 and 116 of the frame which supports the breast-gage are 60 pivoted, at their forward ends, on a stud 119 which is supported by a bracket 120 on the frame of the machine. This stud is located in alinement with the rod 48 on the opposite side of the yoke 96, as shown in 65 Fig. 2.

A rod 121, connecting the side-members 115 and 116, is bent downwardly at its right hand end (see Fig. 1) so as to form a stop 122 (Fig. 5) adapted to engage the upper or tread surface of a heel with which the 70 breast-gage is to coöperate and thus limit the downward movement of said gage.

The breast-gage and its supporting-frame are moved downward, into operative position, by gravity, while they are raised, to 75 remove the breast-gage from the path of movement of the heels on the conveyer, by connection with the supporting frame of the gage-finger 59. For this purpose an arm 123 (Fig. 5) extends upwardly from the side-member 116, in position to coöperate with a pin 124 projecting from an arm 125 which is fixed to the side-member 65 of the frame which supports the gage-finger 59. When the latter frame is rocked by the action of 80 the cam-block 171, as before described, the pin 124 presses the arm 123 in a direction to cause the breast-gage to be raised.

It is desirable to lower the gage-finger 59 into operative position before the last part 90 of the feeding movement of the conveyer, so that the heel on the conveyer may be moved into engagement with this finger, while on the other hand, it is desirable to delay the descent of the breast-gage until the feeding 95 movement has been almost completed, so as to insure that the heel shall have advanced past it. Accordingly, an arm 126 (Fig. 5) is fixed to the side-member 115 of the frame which supports the breast-gage and the lower 100 extremity of this arm, which is bent into an approximately horizontal position, is adapted to engage one of the rollers 28 on the conveyer when the frame is first released by the disengagement of the arm 123 and the 105 pin 124, and thus the breast-gage and its frame are held in raised position for a short interval after the gage-finger 59 has descended, and until the last part of the feed-movement causes the roller 28 in question to 110 move beyond the arm 126.

After both gage-members have been lowered into operative position the breast-gage is moved toward the gage-finger 59. For this purpose a forked block 127 (Figs. 1 115 and 2) is fixed on the rod 114 and is engaged by one end of a lever 128. The other end of this lever is pivoted on a stud 129 which is fixed in a sleeve 130 which connects the side frame-members 115 and 116 and rocks 120 with them on the stud 119. A pin 131 is adjustably fixed in a slot in the lever 128, and this pin engages a slot in a slide-yoke 132 (Fig. 3) integral with a sleeve 133 which is pinned to a rod 134. This rod slides 125 through perforations in the side frame-members 115 and 116. A spring 135, coiled about the left-hand portion of the rod 134, is interposed between the member 115 and a collar 136 fixed on the end of the rod. 130

The pressure of this spring normally holds the parts in the position shown in Fig. 2, with the breast-gage in its most retracted or left-hand position. The sleeve 133 is provided, however, with an arm 138 depending therefrom, as shown in Fig. 5, and the lower end of this arm is in the path of movement of a lug 139, which is screwed upon the left-hand end of the slide-rod 31 and is locked in place thereon by a nut 140. Accordingly, when the rod 31 moves to the right, in the performance of the feed movement of the conveyer, the lug 139, during the last part of this movement, engages the arm 138 and presses it to the right, thus causing the sleeve 133 and the rod 134 to slide to the right. In consequence of this movement the slide-yoke 132 moves the pin 131, thus swinging the lever 128 to the right. This, in turn, causes the block 127, the rod 114, the plate 113, and the breast-gage 110 to move to the right. The breast-gage is, therefore, pressed against the breast of the heel. This movement of the breast-gage is more rapid than that of the conveyer, owing to the multiplying effect of the lever 128, so that it may effectively be performed in a small part of the feed movement of the conveyer. Since the breast-gage is moved positively to its final right-hand position (viewing Fig. 1), it is by this movement that the position of the heel is determined, the gage-finger 59 being adapted to yield to the movement of the heel produced by the breast-gage and serving as a follower to insure that the heel shall be properly engaged by the breast-gage. In order to adjust the operation of the breast-gage for heels of different sizes it is only necessary to move the pin 131 in the slot in the lever 128 (see Fig. 3), thus changing the effective lever-arm through which the slide-yoke acts upon the lever 128.

When the frame which supports the breast-gage is swung upward the arm 138 is disengaged from the lug 139, whereupon the spring 135 returns the breast-gage to its initial position ready for another operation.

As shown in Figs. 2 and 3, an arm 137 is fixed to the sleeve 133 and forked to engage and slide on the rod 114, this arrangement being employed to prevent the sleeve from turning on the rod 134 and thus to hold the yoke 132 parallel with the plane of the lever 128.

The gage-finger 59 and its supporting and actuating means are similar to analogous parts disclosed in the said Patent No. 1,102,311, and are not claimed herein as novel in themselves, but only in so far as they form a novel operative combination with the breast-gage and its supporting and actuating mechanism.

While the present invention has been de-

scribed particularly in its application to a machine for shaping rough heel-blocks, it will be understood that it is not limited to such an application, and that it may be embodied in various other forms within the nature of the invention as it is defined in the following claims.

What is claimed as new, is:—

1. A machine for operating on heels having, in combination, a conveyer which may be loaded with heels; two gage-members; and means for moving the gage-members into the path of movement of the heels and respectively in front and in the rear of a heel on the conveyer, and for moving one gage-member toward the other to cause said members to position the heel between them. 75

2. A machine for operating on heels having, in combination, a conveyer which may be loaded with heels; two gage-members; 85 and means for moving the gage-members into the path of movement of the heels and respectively in front and in the rear of a heel on the conveyer, and for moving one gage-member toward the other to cause said members to position the heel between them, 90 one of the gage-members being yieldingly supported so that the heel is positioned with respect to the surface engaged by the other gage-member. 95

3. A machine for operating on heels having, in combination, a conveyer which may be loaded with heels; two gage-members; and means for moving the gage-members into the path of movement of the heels and 100 respectively in front and in the rear of a heel on the conveyer, and for moving one gage-member toward the other to cause said members to position the heel between them, the gage-member in front of the heel being 105 yieldingly mounted so that the heel is positioned with respect to the surface engaged by the rear gage-member. 110

4. A machine for operating on heels having, in combination, a conveyer which may be loaded with heels; two gage-members; 115 and means for moving the gage-members into the path of movement of the heels and respectively in front and in the rear of a heel on the conveyer, and for moving the rear gage-member toward the front gage-member to position the heel between them. 120

5. A machine for operating on heels having, in combination, a conveyer which may be loaded with heels; two gage-members; 125 and means for moving the gage-members into the path of movement of the heels and respectively in front and in the rear of a heel on the conveyer, and for moving the rear gage-member toward the front gage-member to position the heel between them, the front gage-member being yieldingly mounted so that the position of the heel is determined with respect to the surface engaged by the rear gage-member. 130

6. A machine for operating on heels having, in combination, a conveyer which may be loaded with heels; means for moving the conveyer intermittently; two gage-members; and means for moving the gage-members into the path of movement of the heels and respectively in front and rear of a heel on the conveyer, and for moving one gage-member toward the other, said means operating during a movement of the conveyer. 50
7. A machine for operating on heels having, in combination, a conveyer which may be loaded with heels; means for moving the conveyer intermittently; a gage-member; and means for moving the gage-member into the path of movement of the heels on the conveyer and into engagement with the rear-surface of a heel in the direction of feed so as to advance the heel to a predetermined position on the conveyer. 55
- 10 8. A machine for operating on heels having, in combination, a conveyer which may be loaded with heels; means for moving the conveyer intermittently; a gage-member; and means for moving the gage-member into the path of movement of the heels on the conveyer and into engagement with the rear-surface of a heel in the direction of feed so as to advance the heel to a predetermined position on the conveyer, said means being adjustable to vary the amplitude of the movement of the gage-member. 60
- 15 9. A machine for operating on heels having, in combination, a conveyer for heels, mechanism for transferring heels from the conveyer to a heel receiving station, and means arranged to bring the heels to a definite position on the conveyer, independently of the conveyer, preparatory to the operation of the transferring mechanism on the heels. 65
- 20 10. A machine for operating on heels having, in combination, a conveyer for heels, transfer mechanism movable in a fixed path for receiving heels from the conveyer and delivering them to a heel receiving station in a definite position, and gaging mechanism constructed and arranged to bring a heel on the conveyer into a definite receiving position for the transfer mechanism independently of the movement or the position of the conveyer. 70
- 25 11. A heel machine, having, in combination, a conveyer adapted to receive heels of different sizes at different times, means for invariably advancing the conveyer intermittently a fixed distance irrespective of the size of the heel on the conveyer, and gaging means independent of the conveyer constructed and arranged to bring all sizes of heels to a definite position on the conveyer irrespective of the position to which they have been advanced by the conveyer. 75
- 30 12. A machine for operating on heels having, in combination, a conveyer for heels, means to advance the conveyer, gaging mechanism independent of said conveyer for engaging and bringing the heels to a definite position on the conveyer, and means permitting an adjustment of the gaging mechanism in the line of feed for positioning different sizes of heels. 80
- 35 13. A machine for operating on heels having, in combination, a conveyer for heels, gaging mechanism operated in timed relation to the movement of the conveyer to move the heels relatively to the conveyer either in or opposed to the line of feed to bring the heels to a definite position with reference to a heel receiving station, and mechanism for transferring heels from the conveyer to said station. 85
- 40 14. A heel machine, having, in combination, a conveyer adapted to receive heels, feeding means for said conveyer, and heel gaging means to which the heels are advanced by the conveyer arranged to bring each heel to a like position relative to the conveyer independently of the conveyer. 90
- 45 15. A heel machine, having, in combination, a conveyer adapted to receive heels, feeding means for said conveyer, and heel gaging means separate from the conveyer for engaging opposite sides of a heel and movable intermittently into heel gaging position arranged to bring the heels to a definite position on the conveyer. 95

ERASTUS E. WINKLEY.
